J. RICHARDS.
PUNCHING IRON OR STEEL.

Patented Sept. 28, 1831.

Sept 25 1831

6769X

Richardson Richards. of Ellidge. State of New York.

(Letter Patent.)

The invention referred to in this Letter Patent and making part of the same containing a description in the words of the said Richardson Richards himself of his improvement in the mode of punching or cutting iron & steel by machinery at one operation called the Iron or Steel Cutter or Punch.

To all persons to whom these presents shall come
Richard Richards of the town of Ellidge County of Onondaga and State of
New York Gentleman sends greeting.

Be it known that I the said Richard Richards, have invented constructed
made, and applied to use a new and useful improvement in the mode of Punching
or cutting Iron & Steel by machinery at one operation, called the Iron or Steel
Cutter or Punch. Specified in the words following (viz.)

This improvement is a machine made of iron and consists of the following
principles and made in the manner following (viz.)

I have a piece of iron twelve inches long and two inches square for
the bottom part of said machine which lies horizontal and is fastened
firm to a piece of timber. The top piece, is a piece of iron nine inches
long and two inches square, lying directly over the bottom piece & leaving
a space of 2 inches between them, and having the ends even at the
back, and which has a projection on the lower piece at the forward
end of three inches. These two pieces are connected together at
the back end by a circular spring which raises the top piece which also
raises the punch or cutter out of the work, on the top piece on the
forward end I have my punch or cutter, which is let into the end of
the top piece by a slot or groove in the top piece. The punch or cutter is
fastened on to the top piece by a screw and is made with a shoulder that
lets directly under the top piece to keep it firm, the punch or cutter being
perpendicular and is worked perpendicular. The die stands on the lower
piece & is made of iron & steel which is of sufficient strength to stand upon

9/28/83

6769X

the bottom piece & turns down on each side of the lower piece, in and out of the die, on the part which turns down is a small piece to guide the die so that the punch or cutter will easily fit into the die.

On the forward end of the lower piece I have a screw or key to set the die back against the punch or cutter, the Punch & Die may be made of any shape that may be required to make any impression to punch any kind of work.

On each side of the top and bottom piece is a stop that reaches above the top piece far enough to support the lever above, the straps are connected together on the under side of the lower piece so that the lever draws up on the lower piece and down on the upper piece, the straps stand directly back of the die.

The lever works on a bolt that passes through the top of the straps & the end of the lever the lever purchase is on the top of the top piece, the fulcrum for common cutting is one inch, when it rolls under, it brings the fulcrum more perpendicular & shorter and increases the power very much, the lever has a turn down at the fulcrum so that the end stands perpendicular while the lever lies horizontal.

There are two iron posts fixed to the bottom piece one inch from the back end (one post on each side) six inches long, a bolt passes through the top of the posts and the end of the top piece for the purpose of supporting the end of the top piece in punching or cutting heavy work.

I calculate to use this machine for punching Steam Banging blocks, Wagon and carriage tires, cut mill saws and other cast iron & especially old saws, and do all manner of punching from 1/8 inch to 1/2 inch for smith work.

In testimony that the above is a true specification of my said improvement as above described, I have hereunto set my hand and seal, the twentieth day of August in the year of our Lord one thousand eight hundred and thirty one,

(Witnesses).
